WALL SUPPORT FOR HANGING ARTICLES OR SIMILAR ARTICLE

Estelle Berman, New York, N. Y.

Application February 15, 1949, Serial No. 853

Term of patent 14 years

(Cl. D44—29)

To all whom it may concern:

Be it known that I, Estelle Berman, a citizen of the United States, residing at New York city, in the county of Bronx and State of New York, have invented a new, original, and ornamental Design for a Wall Support for Hanging Articles, or Similar Article, of which the following is a specification, reference being had to the accompanying drawing, forming part thereof.

In the drawing

Fig. 1 is a front view of a wall support for hanging articles, showing my new design;

Fig. 2 is a side view thereof, and

Fig. 3 is a rear view of the wall support shown in Fig. 1.

I claim:

The ornamental design for a wall support for hanging articles, or similar article, substantially as shown.

ESTELLE BERMAN.
